CLAIM

The ornamental design for the power unit cover for a portable hardfile storage device, or the like, as shown and described.

DESCRIPTION

FIG. 1 is a top front perspective view of a power unit cover for a portable hard file storage device or the like showing our new design;

FIG. 2 is a top plan view thereof on an enlarged scale; FIG. 3 is a front elevational view thereof on an enlarged scale;

FIG. 4 is a bottom plan view thereof on an enlarged scale;

FIG. 5 is a rear elevational view thereof on an enlarged scale;

FIG. 6 is a right side elevational view thereof on an enlarged scale;

FIG. 7 is a left side elevational view thereof on an enlarged scale; and

FIG. 8 is a top rear perspective view thereof.

The hard file module is shown in broken lines for illustrative purposes only.

FIG. 1
